UNITED STATES PATENT OFFICE

VOJTECH PUC, OF PRAGUE, CZECHOSLOVAKIA

ATTACHMENT FOR BAGGAGE AND THE LIKE

Application filed September 24, 1931. Serial No. 564,914.

This invention relates to an attachment for baggage and the like. It consists essentially of a card made of stiff paper, leather, paste board or the like which at one end 5 forms a narrow fixing band. At the end of this fixing band is secured the pin part of a bachelor's button, while the spring part of the button is secured to the card. The arrangement is such that the pin part of the 10 button consists of a cylindrical hollow shank drawn out of a disc which is curved in near its end, while tongues stamped out of the disc are pushed through the fixing band and bent over it so that the pin part is secured 15 to the band.

The spring part of the button consists of the known perforated disc which has radial slots from the edge of the hole dividing the inner part of the disc into resilient sectors, 20 the inner edges of which catch in the notch of the pin which is introduced.

This disc is secured by the marginal tongues of a cap lying on the other side of the card which are pushed through the card 25 and bent over the disc.

The fixing band is put in a narrow part of the package, for example, the handle or a part of a strap, and the pin part is pressed into the spring part of the button. The 30 card is secured to the package by means of the pin part held in the cap of the resilient part in the notch of which the edges of the disc sectors engage.

A constructional example of the fixing card 35 is illustrated in the accompanying drawing. Fig. 1 shows a side elevation and Fig. 2 a section on the line $x-x$ of Fig. 1.

The card 1 has at one end the fixing band 2.

At the part 3 where the card becomes a 40 band is secured the resilient part of the bachelor's button.

The spring part consists of the perforated disc 4, the inner part of which is divided into resilient sectors 5 by radial slits from the 45 edge of the hole. This disc lies on one side of the card. On the other side of the card is a cap 6 with marginal tongues 7 which are pushed through the card and bent over the perforated disc.

The pin part is secured to the end of the

fixing band. It consists of a cylindrical hollow shank 9 drawn out of the disc 8 on which is provided the notch 10. Tongues 11 pressed out of the disc 8 which are pushed through the band and bent over on to it secure the pin 55 part to the band.

The card is secured to the article, for example the baggage, by passing the band 2 round a narrow part, for example the handle of the article, and then the pin part is pressed 60 into the resilient part. The edges of the disc sectors 5 engage in the notch 10 of the shank 9 and the end of the band 2 is thereby fastened firmly and permanently to the card 1.

What I claim is:

An attachment for baggage and the like consisting in the combination of a card with a narrow band running from one end of the card and a bachelor's button, the spring part 70 of the button which is arranged in the part of the card which runs into the band and consists of a perforated disc lying on one side of the card with slits running from the edge of the hole, and a cap on the other side of the card, the marginal tongues of which are pushed through the card and bent back over the disc.

In testimony whereof I have signed my name to this specification.
